UNITED STATES PATENT OFFICE

127,486

DESIGN FOR A PLATE OR SIMILAR ARTICLE

Pascal L'Anglais, New York, N. Y., assignor to Mayer China Company, Beaver Falls, Pa., a corporation of Pennsylvania

Application April 3, 1941, Serial No. 160,115

Term of patent 14 years

To all whom it may concern:

Be it known that I, Pascal L'Anglais, a citizen of the United States, residing at New York city, New York, have invented a new, original, and ornamental Design for a Plate or Similar Article, of which the following is a specification, reference being had to the accompanying drawing, forming part thereof.

The drawing is a top plan view of a plate showing my new design.

The dominant feature of the design is the surface ornamentation appearing on the article, and while shown applied to a plate, said ornamentation is intended to be applied to other similar articles.

I claim:

The ornamental design for a plate or similar article, substantially as shown and described.

PASCAL L'ANGLAIS.
